UNITED STATES PATENT OFFICE

CHARLES A. WOOLSEY AND HENRY V. BOWMAN, OF MINNEAPOLIS, MINNESOTA

CRATE

Application filed March 22, 1930. Serial No. 438,083.

This invention relates to improvements in crates and more particularly to crates of the type used for transporting milk bottles.

An object of the invention is to provide a crate of simple and inexpensive construction, the walls of which are composed of slats arranged one above another and provided at the corners of the crate with means whereby said slats may be secured together to form the walls of the crate without the use of lacing wires such as are now commonly used in structures of this kind.

A further object is to provide a crate having walls composed of slats arranged one above another and plates fitting the corners of the crate and seated against said slats and provided with means adapted to be embedded in the slats, and anchor plates being interposed between the slats at the corners of the crate and having means adapted to engage surfaces of said slats opposite from those engaged by said corner plates, and means for connecting together said corner and anchor plates to secure the slats in position.

Other objects of the invention will appear from the following description and accompanying drawings and will be pointed out in the annexed claims.

Features of the invention reside in the specific construction of the corners of the crate; in the provision of the corner plates seated against the outer corners of the crate walls and having longitudinally formed channels adapted to be seated in the outer surfaces of the slats; in the provision of the anchor plates interposed between said slats at the corners of the crate each of which is provided with ears adapted to engage the inner surfaces of the slats, and has apertures adapted to be aligned with the channels in said corner plates; in the provision of the locking wires provided at the corners of the crate and adapted to be inserted through the apertures in said anchor plates and through the channels in the corner plates whereby the slats will be demountably secured between said corner and anchor plates; in the general construction and arrangement of the corner and anchor plates in connection with the locking wires;

and, in the unique construction of the grid structure provided in the crate for supporting in spaced relation within the crate, such articles as, for example, milk bottles.

In the accompanying drawings, there has been disclosed a structure designed to carry out the various objects of the invention, but it is to be understood that the invention is not confined to the exact features shown as various changes may be made within the scope of the claims which follow.

In the drawings:

Figure 1 is a perspective view showing the improved crate with one of the corner plates broken away to more clearly illustrate the construction at the corners of the crate;

Figure 2 is a perspective view showing one of the corner irons removed from a bottom corner of the crate and one of the corner plates swung outwardly to permit the removal of a damaged slat from a wall of the crate;

Figure 3 is a sectional view on the line 3—3 of Figure 4 showing the construction of the grid structure within the crate;

Figure 4 is a plan view of the crate partially broken away;

Figure 5 is an enlarged detail sectional view, showing a corner of the crate and the manner in which each corner plate may be so swung outwardly when one of the locking wires are removed, to permit the removal of a damaged slat from the crate wall;

Figure 6 is a perspective view showing a corner of the crate and the general arrangement of the corner and anchor plates, and the manner of securing these parts together by the locking wires;

Figure 7 is a perspective view of one of the corner irons removed from the crate;

Figure 8 is a detail sectional view on the line 8—8 of Figure 3, showing the means for retaining the locking wires in operative position;

Figure 9 is a detail sectional view on the line 9—9 of Figure 3;

Figure 10 is a perspective view of the grid structure only; and

Figure 11 is a view showing a blank from which the grid reinforcing plates are formed.

The novel crate featured in this invention comprises side and end walls 2 and 3, respectively, as shown in Figure 1. The side walls are composed of slats 4, 5, 6, and 7, arranged one above another and secured together at the corners of the crate, as will be hereinafter described. The end walls are composed of slats 8, 9, 10, and 11, the ends of which are engaged with the slats of the side walls, and alternately arranged with respect thereto, as best shown in Figure 1. Suitable hand holes 12 are provided in the end walls of the crate.

The means provided for securing together the side and end walls at the corners of the crate is best shown in Figures 2, 5, and 6, and consists of corner plates 13 of angular cross-section, and each provided with longitudinally extending channels 14 adapted to be seated in elongated recesses 15, provided in the outer surfaces of the slats adjacent the ends thereof. The recesses 15 provided in the slats of each crate wall are alined as best shown in Figure 1, so that when the slats are assembled in the walls and the corner plates 13 are mounted thereon, the channels 14 provided at the marginal edges of the corner plates, will be seated in the alined recesses 15, as clearly shown in Figure 5. The lower end portion 16 of each corner plate 13 is offset inwardly, as shown in Figure 9 and is seated in the bottom of a recess 17 provided at the ends of the bottom slats, as best shown in Figures 6 and 9.

Anchor plates 18 are interposed between the slats at the corners of the crate as best shown in Figure 6 and cooperate with the corner plates 13 to secure the slats in proper position. Each anchor plate is provided with upwardly and downwardly turned ears 19 and 21, respectively, adapted to engage the inner surfaces of the slats, as shown. Each anchor plate is further provided at its outer edges with offset portions 22 having suitable apertures 23 therein, each adapted to receive a suitable securing or locking wire 24. As shown in Figures 6 and 8, the apertures 23 are disposed in alinement with the channels 14, so that the wires 24 may be inserted through the apertures 23 and channels 14, and thus secure the slat ends in position therebetween. The channeled edges of the corner plates 13 are provided with suitable slots or slits 20 adapted to receive the portions 22 of the anchor plates 18.

Corner irons 25 are secured to the lower corners of the crate walls, as shown in Figures 1 and 2. Each corner iron 25 extends inwardly beneath the lower edges of the bottom slats 7 and 11 and have upturned lugs 26 adapted to be seated against the inner surfaces of the bottom slats, as will be understood by reference to Figure 9, which clearly illustrates the assembly of the parts at the lower corner of the crate. Apertures 27 are provided in the outer wall portions of the

corner irons 25 and are alined with similar apertures 28 provided in the inner lugs 26. The bottom slats 7 and 11, and the offset portions 16 of each corner plate 13, are provided with apertures which are alined with the apertures 27 and 28 in the corner iron, when the latter is properly positioned in the crate corner, so as to permit the insertion of suitable rivets or bolts through said alined apertures to secure the parts together.

When the crate walls are assembled, as shown in Figure 1, the lower ends of the rods 24 will be positioned upon the upper edges of the walls of the corner irons 25, and the upper ends thereof against the upper ends of the channels 14, as clearly shown in Figure 8, thereby retaining the locking wires in operative positions. The lower portions of the corner irons 13 are provided with oppositely extending lugs 31 adapted to overlie the wires 24 when the crate walls are assembled.

Suitable brackets 32 are provided in the upper, inner corners of the crate and project above the upper edges of the top slats as shown in Figures 1, 2, and 3, to provide means for nesting or stacking the crates, one upon another. When two crates are stacked one on top of the other, the brackets 32 on the lower crate will project upwardly into the bottom of the top crate and thereby retain the crates in stacked position thereon.

The crate is here shown adapted for use to contain milk bottles or similar articles, and is provided with a grid-like structure constituting the bottom of the crate and also the separators or partitions between the bottles or articles to be transported therein. The bottom of the crate is composed of a plurality of spaced apart rods 33, here shown extending lengthwise of the crate and having their terminals suitably secured in the bottom slats 11 of the end walls, as indicated at 34 in Figure 3. Cross members 35, preferably of sheet metal and of channel cross section, are mounted upon the rods 33 in spaced relation, as shown in Figures 3, 4, and 10. Lower portions of the upright walls of the cross members 35 are bent outwardly in opposite directions, as shown in Figures 3 and 10, to provide alined apertures or guides 36 adapted to receive cross rods 37 having their terminals suitably secured in the bottom side slats 7, as shown in Figure 1. The rods 37 cooperate with the cross members 35 to provide supports for the rods 33 forming the bottom of the crate.

The partitions in the crate are formed by a plurality of rods 38 and 39 extending lengthwise of the crate, and cross rods 41 extending crosswise of the crate. The lower rods 38 pass through suitable apertures provided in the cross members 35 and have their terminals suitably secured in the lower end slats 11, by means of washers and by upset-

ting the ends of the rods, as indicated at 42 in Figure 3. The upper rods 39 have their terminals similarly secured in the end slats 10, as indicated at 43. Suitable connectors 44 are provided between the cross members 35 and the upper rods 39 and 41, as shown in Figures 3 and 4. These connectors are preferably U-shaped in cross section and have their lower end portions flattened and suitably secured to the cross members 35 by such means as rivets 45, best shown in Figures 3 and 10. The upper ends of the connectors 44 are apertured to receive the rods 39 and 41, as shown. The upper ends of the connectors 44 are securely fixed to the rods 39 and 41 by means of reinforcing plates 46, shown in Figures 4, 10, and 11, and have their marginal edges bent downwardly and into engagement with the rods as shown in Figures 3 and 4. The edges 47 of the plates 46 are concaved, as shown in Figure 4, to provide circular compartments for the bottles as will readily be understood by reference to Figures 4 and 10.

From the foregoing, it will readily be seen that the rods 33, 37, 38, 39, and 41, and the cross members 35, connectors 44, and plates 46 cooperate to provide a very rigid and substantial grid structure forming the bottom and partitions for supporting the bottles in the crate. The entire grid-like structure is supported within the crate because of the terminals of the rods being suitably secured to the slats of the crate walls, as above described.

The construction of the novel crate herein disclosed is such that if one of the slats in the crate walls becomes damaged or broken and has to be replaced, it may readily be detached or removed from the crate without disassembling the entire crate.

Figures 2 and 5 illustrate a manner of removing a slat from a wall of the crate by simply removing the corner irons 25 from one corner of the box and partially removing one of the vertically disposed corner plates 13. To thus remove a slat from a wall of the crate, the rivets 48 securing the upper end of one of the corner plates 13 to the crate walls and the rivets 49 securing the lower end of said corner plate to the crate walls, are removed, and the corner iron 25 at that corner of the box detached from the crate, as shown in Figure 7. The wire 24 is then withdrawn from the channel 14 and the anchor plates 18, whereupon the corner iron may be swung outwardly to the full line position, shown in Figure 2 and the dotted line position indicated in Figure 5. The wire 24 at the opposite end of the crate may be removed by bending the projection 31 outwardly as shown in Figure 2. When the parts are thus positioned, the damaged slat, here shown as being the second one from the top, is swung outwardly, as indicated in full lines in Figure 4, whereupon the corner plate

at the opposite end of the crate will yield sufficiently to permit the slat to become disengaged therefrom without the necessity of having to remove the rivets 48 and 49 at that end of the crate. The new slat to be substituted for the damaged one is then inserted between the corner plate 13 and the ears 21 of the anchor plates 18 at the left hand end of the crate, when viewed as shown in Figure 2, and the opposite end of the slat is then swung into place between the slats 4 and 6, whereupon the corner plate 13 at the right hand side of the crate, when viewed as shown in Figure 2, is swung back into place and the wire 24 inserted into the channel 14 back of the projections 31 at the lower ends of the corner irons 13 and through the alined apertures provided in the corner plates 18, as clearly shown in Figures 6 and 9. The corner iron 25 is then secured to the lower corner of the crate by means of the rivets 49 and the upper end of the corner plate 13 secured to the walls by the rivets 48, thereby securely connecting together all parts. The wire 24 at the opposite end of the crate may be inserted into the channel 14 and the projection 31 bent back to its normal position to retain the wire in locking position. The upper edges of the walls of the corner irons 25 are positioned to engage the lower ends of the wires 24 to retain them in locking position. The brackets 32 at the upper inner corners of the crate are secured to the walls of the crate by the rivets 48 which pass through the corner plates 13, slats 4 and 8 and suitable apertures provided in said brackets.

In some instances, it may be necessary to remove the corner plates 13 from two corners of the crate as, for example, if two or more slats should be damaged. This may readily be done without interfering with the corners at the opposite side of the crate so that the work of repairing a damaged crate is greatly simplified. It will also be noted that the wires 24 which lock together the anchor and corner plates do not pass through apertures provided in the slats, as do the lacing wires now commonly used in crates of this character. In the crate herein disclosed, the wires 24 are exposed and may readily be removed or detached from the crate walls by simply removing the corner irons 25 at the bottom of the crate. This feature also simplifies the operation of assembling.

The lower edges of the crate walls are suitably reinforced by means of metallic rails 51 and 52 suitably secured to the lower slats 7 and 10 respectively. These rails provide runners for the crate and at the same time, prevent the lower edges of the slats from becoming damaged as a result of rough handling, to which crates of this character are often subjected.

We claim as our invention:

1. A crate having walls composed of slats

arranged one upon another and provided with alined recesses adjacent to the corners of the crate, angle plates fitting the outer corners of the crate and having channels adapted to be seated in said recesses, anchor plates interposed between the slats at the corners of the crate and having ears formed thereon adapted to engage inner surfaces of said slats, said anchor plates having apertures therein adapted to be alined with said channels, and

10 a wire inserted in each channel and through the apertures in said anchor plates alined therewith, thereby to secure together said corner plates, anchor plates and wall slats.

15 2. A crate having walls composed of slats arranged one upon another and provided with vertically disposed alined recesses adjacent to the corners of the crate, angle plates fitting the outer corners of the crate and provided with longitudinally extending channels at the opposite edges thereof adapted to be seated in said recesses, anchor plates interposed between the slats at the corners of the crate and having oppositely extending 20 ears formed thereon adapted to engage inner surfaces of said slats, said anchor plates having apertures therein adapted to be alined with said channels, a locking wire adapted to be inserted in each channel and through the 25 apertures in said anchor plates alined therewith, thereby to secure together said corner plates, anchor plates and wall slats, corner iron fitting over the lower end portions of said angle plates and having portions extending under the lower slats and upwardly 30 into the crate, and means for securing said corner irons to the angle plates and slats.

35 3. A crate having walls composed of slats arranged one upon another and provided with vertically disposed alined recesses in the outer surfaces thereof and adjacent to the corners of the crate, angle plates fitting the outer corners of the crate and provided with longitudinally extending channels formed in 40 the marginal edges thereof and adapted to be seated in said recesses, anchor plates interposed between contiguous slats at the corners of the crate and having ears formed thereon adapted to engage inner surfaces of 45 adjacent slats, said anchor plates having apertures therein adapted to be alined with the channels in said anchor plates, a wire inserted in each channel and through the apertures in said anchor plates alined therewith 50 to secure together said angle plates and anchor plates with the wall slats secured therebetween, and corner irons secured to the lower corners of the crate and engaging said angle plates to retain said locking wires in operative position.

55 4. A crate having walls composed of slats arranged one upon another and provided with alined recesses adjacent to the corners of the crate, angle plates fitting the outer corners of the crate and having channels adapted

to be fitted in said recesses, anchor plates interposed between the slats at the corners of the crate and having portions adapted to engage inner surfaces of said slats, said anchor plates having apertures therein adapted to be alined with said channels, and a wire inserted in each channel and through the apertures in said anchor plates, thereby to secure together said corner plates, anchor plates and wall slats.

70 5. A crate having walls composed of slats arranged one upon another with their ends alternately disposed at the corners of the crate, said slats having alined recesses in the outer faces thereof adjacent to the corners of the crate, angle plates fitting over the outer corners of the crate and seated against said slats, said plates having portions adapted to be seated in said recesses, anchor plates interposed between the slats at the corners of the crate and having apertures therein alined with said recesses, said anchor plates having portions adapted to engage inner surfaces of said slats adjacent to the corners of the crate to prevent inward movement of the slats, and means extending lengthwise through said alined recesses and engaging portions of said corner plates and also traversing the apertures in said anchor plates whereby said parts will be detachably secured together.

75 6. A crate having walls composed of slats arranged one upon another with their ends alternately disposed at the corners of the crate and having vertically disposed alined recesses in the outer faces thereof adjacent to the corners of the crate, corner irons fitting over the outer corners of the crate and concealing the ends of said slats, said corner irons having channel portions adapted to be seated in said recesses, anchor plates interposed between the slats at the corners of the crate and having portions engaging inner surfaces of said slats, said anchor plates having apertures therein alined with said recesses, and a wire extending lengthwise through the channel portions of the corner irons seated in said recesses and also traversing the apertures in said anchor plates, whereby said slats will be secured in position at the corners of the crate.

seated in each channel and passing through the apertures in said plate portions, whereby said corner irons, plates, and slats are secured together.

- 5 8. A crate having walls composed of slats arranged one upon another with their ends alternately disposed at the corners of the crate, angle plates fitting over the corners of the crate and concealing the ends of the slats,
10 said angle plates having horizontally disposed slits therein, anchor plates interposed between contiguous slats at the corners of the crate and having portions engaging inner surfaces of certain of said slats, said anchor
15 plates also having portions fitting into the slits in said angle plates and provided with suitable apertures, and a locking wire traversing the apertures in said anchor plates and seated against outer surfaces of said angle
20 plates whereby the ends of the slats will be detachably secured together at the corners of the crate.

In witness whereof, we have hereunto set our hands this 19th day of March, 1930.

25 CHARLES A. WOOLSEY.
HENRY V. BOWMAN.
